ELECTRIC ACCUMULATOR

Henri Georges André, Montmorency, France, assignor to Yardney International Corp., New York, N. Y., a corporation of New York

Application November 27, 1950, Serial No. 197,730
In France November 29, 1949

3 Claims. (Cl. 136—6)

1

This invention relates to a battery of the type disclosed in my co-pending U. S. Application Ser. No. 738,702, filed April 1, 1947. In such a battery, or reversible electro-chemical energy generator, or accumulator, the ionic exchanges between the electro-chemically active substances are effected through a semi-permeable material which serves as a separator member and is impregnated with electrolyte.

The invention is more particularly directed to such accumulators wherein the electro-chemically active materials of opposite polarity are applied under pressure against the opposite sides of such a semi-permeable separator or diaphragm member.

The procedure of applying electro-chemically active materials under pressure against a diaphragm has constituted a decisive advance in the art of reversible electro-chemical energy-generators. It has made it possible to limit the amount of electricity present in an accumulator, and to fulfill its operative function in retention within a solid material rather than in the liquid state, which, aside from obvious facilitation of handling and manipulation, has completely altered the very character of the electro-chemical reactions involved.

However, the construction of such accumulators has until now raised certain difficulties. Thus, taking the instance of an accumulator wherein the electro-chemically active substances are silver and zinc and the semi-permeable material is the regenerated cellulose sheet material known as cellophane, whereas such an accumulator is easy enough to make in the laboratory under the guidance of a skilled expert and when resorting to all the usual precautions taken in the construction of a prototype model, the results are found to be much less uniform where the production is entrusted to workers, however skilled, who cannot be expected to display the same amount of care as the engineer or scientist, if only for considerations of output.

It has been sought for some time to ascertain the causes of such lack of uniformity and to explain why, while some of the accumulators produced do possess the characteristics expected of them, a number of specimens were ordinarily produced in which either the capacity was too low or the useful life too short, even though no differences in structure could be detected as compared to the satisfactory units.

While it had been seen that the successful operation of the accumulator depended on the pressure prevailing in it between the active materials

5 and the diaphragms, it was believed that this pressure could be allowed to vary over quite a wide range without producing any critical modifications in the characteristics of the unit. As the said pressure results from a swelling of the semi-permeable material owing to its impregnation by electrolyte, it was endeavored to obtain a satisfactory operative pressure by suitably selecting, in an approximate manner, the thickness or depth of the semi-permeable member in its dry state relatively to the clearance reserved for it in the tank by the active materials, such that, after swelling, the resulting pressure would approximate that which was believed to prevail in a previously constructed accumulator which had displayed good results.

Such an empirical procedure, in addition to the irregular results to which it is conductive as mentioned hereabove, provides no means of transferring production from one type of accumulator to another type differing from the first in electrical power capacity, or by its ability for rapid discharge, etc.

20 It is an object of this invention to meet this inadequacy of the prior art. It is an object to provide an accumulator of the type specified wherein the electro-chemically active substances are applied under pressure against opposite sides of a semi-permeable member, which may be expected with positive certainty to yield optimum results, regardless of its capacity. Another object is to provide a means of selecting at will, from among the various known forms of electrode construction, that particular form which will lend itself to easy construction while leading to the desired result, without any danger of such selection being adversely reflected in the characteristics of the apparatus, contrarily to what almost inevitably occurred heretofore.

25 Systematic tests have been conducted to ascertain the conditions to be fulfilled in order to obtain with certainty successful operation in an accumulator of the specified type. For this purpose, it has been sought to define the structural characteristics to be imparted to the electrodes and, more specifically, the relative thickness or depth dimensions to be imparted to the active substances and diaphragms in order to secure, within the finished accumulator, a predetermined value of the pressure under which the active substances are applied against the opposite sides of said diaphragms.

In the accompanying drawing:

Fig. 1 illustrates a testing device which is useful

in the construction of a battery according to the invention;

Fig. 2 is a pressure diagram obtained with the device of Fig. 1;

Figs. 3 and 4 are further diagrams illustrating important characteristics of a battery according to the invention; and

Fig. 5 is a fragmentary section through a battery representing an embodiment of the invention, enough being shown of the battery to illustrate the relative arrangement of its component parts.

An accumulator of the type specified comprises a multiplicity of layers or laminae of positive substance alternating with a multiplicity of layers or laminae of negative substances, each pair of adjacent layers or laminae of opposite polarity being separated by a diaphragm and the entire laminated assembly being disposed in a container.

Let l be the distance between the parallel sides of the container extending in a direction parallel with the layers of active substances and the diaphragms, and e the combined thickness of the layers of active substances in the dry state; then the said pressure which prevails after the electrolyte has been added depends on the ratio a of the difference $(l-e)$ or clearance i , left free in the container by the active substances for receiving the diaphragms, to the sum total of the thickness dimensions d of said diaphragms in the dry state.

The curve representing the variations of said pressure P versus those of the ratio a has been plotted. For this purpose, the device diagrammatically illustrated in Fig. 1 has been designed. This apparatus essentially consists of a box-shaped container 10 two of the side walls of which are shown at 11 and 12 and the bottom at 13. The walls and the bottom have sufficient rigidity such that they may be regarded as undeformable under the operating pressures developed.

Secured to the upper surfaces of said side walls 11 and 12 is a cross member 14 formed in its center with a hole 15 for guiding a piston rod 16 having rigidly secured to its lower end a piston 17 substantially rectangular in horizontal cross section, and adapted for sliding movement in the container 10, sufficient clearance being provided in the sliding fit of the piston in the container for allowing substance, especially liquid, to pass from one to the other of the two chambers or compartments 18 and 19 defined by the piston in the container. Upstanding on the container is a structure 20 including two uprights 21 and 22 and an upper cross-bar 23 which supports at its center a preferably threaded rod 24 cooperating with a complementary hole formed in the cross-bar 23. The rod 24 carries at its base a small plate 25 which serves as an abutment for a compression coil spring 26 of calibrated resiliency, and abutting at its lower end against a plate 27 rigid with the piston rod 16. The plate 27 supports a pointer 28 adapted to cooperate with a scale of calibrations 29 supported from the crossbar 23.

A laminated pile of cellophane sheet elements, in the dry state, of measured thickness in the uncompressed condition, is inserted into the container 10 under the piston 17. The said thickness or depth of the pile in uncompressed condition, referred to as d , may, indeed, be measured in the apparatus itself, by reading first the position of the pointer 28 when the piston 17 rests on the

bottom 13 of the container, and then its new position with the piston resting on the top of the pile of laminated sheets substantially under zero pressure. Starting from this condition, the piston 17 is raised by a vertical distance i , this distance being ascertained by means of the pointer 28 cooperating with the calibrated scale 29. The vertical position of the plate 25 is then so adjusted that, for this position, the compression of the spring is nil, while as soon as the plate is raised above this position the spring will be subjected to compression.

The swellingly acting electrolyte, e. g. a water solution of potassium hydroxide, is then introduced into the compartment 19 by the simple procedure of pouring it onto the piston 17 whence it flows into the lower compartment through the clearance intentionally provided between the sides of the piston and the walls of the container 10.

The cellophane sheet elements contained in the compartment 19 swell; the stack increases in thickness until it reaches up to the under face of the piston 17, and thereafter, on further swelling, pushes up the piston against the action of the spring 26 which contracts. The sag of the spring may be indicated by the displacement of the pointer 27 over the scale 29; this reading yields, with due allowance for the initial adjustment, an indication of the pressure P . The curve of variation of this pressure as a function of the above-defined factor a may thus be plotted. A typical such curve has been shown at A in Fig. 2, wherein the values of the factor a are plotted in abscissae and the pressures P (expressed in kg./sq. dm.) in ordinates. It can be ascertained from this curve that the pressure increases as the fourth power of the factor a .

This surprising discovery explains the irregular results obtained in the past in the construction of such accumulators, in that it shows that a very small difference in the thickness of the diaphragms relatively to the total clearance, provided for them in the container by the active substances, can entail very considerable differences in the operating pressures.

Thus, in this connection, the invention is based upon the discovery of the critical character of said diaphragm thickness, and of the need for selecting such thickness with the utmost care and accuracy. From this it can be inferred that an essential specification in the manufacture of accumulators designed for operation in the manner described lies in the number of sheets of regenerated cellulose or cellophane (since their individual thickness is, in practice, very nearly constant) which are to be interposed, whether rolled or packed around or otherwise, between the active substances of opposite polarity in the accumulator.

Actually the pressure under which the active substances of opposite polarity are applied against the diaphragms within the accumulator is not, strictly speaking, the pressure defined by the above-described curve A as a function of the factor a ; thus, allowance must be made, in the first place, for the contraction or shrinkage of the active substances which occurs in the course of operation of the accumulator, and, moreover, for the slight distortion assumed by the container under the action of the forces developed against its opposite walls. The compression curves which make allowance for both these factors have also been plotted.

To take into account the compression of the

active substances, complete accumulator units have been dismantled, which present structural characteristics similar to that of the type being investigated—and operating with good results—after such units have been effectively operated for a substantial time, so that they could be considered as having reached their normal operating state. The thickness of the electrodes is measured, and it was found that a certain degree of contraction has occurred therein relatively to the thickness of said electrodes in the dry state.

The corrected compression curve which makes allowance for this contraction is shown at B in Fig. 2, and it is seen that its general shape is exactly similar to that of the curve A, and that it can be regarded as being the curve A merely shifted in a direction parallel to the axis of abscissae. Comparison between curves A and B shows that, in the instance under investigation, the contraction of the active substances amounts to about 10%.

Lastly, the corrected curve which, in addition to the contraction of the active substances, at the same time takes into account the slight expansion of the container is shown as the curve C, which may also be seen as resulting from the curves A and B by a translation parallel to the axis of abscissae.

This curve C provides the manufacturer with accurate data on the thickness which is to be imparted to the semi-permeable substance taken in the dry state, or, in practice, the number of sheets of cellophane to be used for each electrode, in order to obtain, in the operation of the accumulator under construction, a predetermined value for the pressure of application of said active substances against the cellophane separators.

It is found, by way of example, that in order to obtain a normal operating pressure of 20 kg./sq. dm. the combined cellophane thickness should be selected such that the factor a should be slightly higher than 2.30. This information is especially valuable in view of the experimental results, indicated hereafter, provided by very numerous tests carried out with the object of ascertaining the most favorable internal pressure for optimum operation of an accumulator.

With the above teachings in mind, accumulator units have been constructed differing from one another in their internal operating pressure, that is the pressure of application of the active substances against the separator diaphragms. Then the electric capacities of each of these units was plotted as a function of the said pressure, for various rates of discharges. Curves were thus obtained such as shown at D, E, F on the diagram of Fig. 3, wherein the pressures in kg./sq. dm. are plotted in abscissae and the capacities in amp. hrs. in ordinates.

The curve D was found for complete discharges of the units in two hours, the curve E for complete discharges of the units in ten hours, and the curve F for complete discharges in 24 hours. These curves show that optimum capacity, in each of the three cases, is for an internal pressure approximating 20 kg./sq. dm., and that this capacity drops off but slowly as the pressure is decreased from 20 kg./sq. dm. to 15 kg./sq. dm., while it drops off at a comparatively very fast rate as the pressure is increased above 20 or 21 kg./sq. dm.

Keeping in mind both the curves of Fig. 2 and those of Fig. 3, the reason why accumulator units produced in an apparently quite similar

manner displayed such wide differences in service performance becomes obvious. It is seen that it is sufficient for the internal pressure to vary only by one or two kg./sq. dm. for the capacity to be cut down by 50%. Now, a variation of 1 or 2 kg./sq. dm. corresponds to only a few percent variation in the ratio a . In practice, this means that the insertion of only one or two cellophane sheets too many during the construction of an accumulator is enough gravely to impair the ultimate operating characteristics of the unit.

Further experiments have been conducted on accumulators possessing different internal pressures with the object of ascertaining the influence of such pressure on service life. The results of these tests are summarized in graphic form in the curve of Fig. 4, wherein internal pressure is plotted in abscissae versus the number of the unit's useful operating cycles in ordinates. The curve G thus obtained displays a maximum for a pressure approximating 20 kg./sq. dm., for which the number of operating cycles attains 400. It decays, though slowly, as the pressure is increased above the said value, but on the other hand it falls comparatively rapidly as the internal pressure is reduced below 20 kg./sq. dm.

These last-mentioned experiments thus demonstrate that, where it is desired to obtain an accumulator having a long service life, it is necessary that the pressure be not substantially lower than 20 kg./sq. dm. For reasons similar to those explained above in the discussion of the curves D, E, F, it is seen that the lack of only one or two sheets of cellophane has a very adverse effect on the operation of an accumulator.

Now to combine the teachings resulting from the consideration of Figs. 2 to 4, the necessary conclusion is that both the excess and the deficiency of one or two sheets of cellophane result in highly detrimental consequences on the accumulator performance, and that the prescriptions as to the number of cellophane sheets used to wrap the active substances should be scrupulously followed. Such prescriptions, which are very easy to observe strictly, by a mere effort of attention, make it possible to provide accumulators which possess all the high qualities expected of them as resulting from the tests conducted on the prototype model. The simplicity of the improvement provided by this invention, far from detracting from its importance, confers to it an essential value, inasmuch as it makes it possible to achieve considerable improvement in production without increasing the cost of manufacture and without requiring any alteration in plant.

Theoretical considerations may be put forward to explain the results yielded by the practical tests described herein. An excessive pressure applying the active substances against the diaphragms tends to retard, and finally completely to inhibit, the ion diffusion and exchanges.

On the other hand, in the case the pressure of application is too low, the electrodes are insufficiently constrained, so that the active substances, including especially the negative active substance, tend to drop to the bottom of the container.

However that may be, it was impossible to predict the decisive importance, from the standpoint of operating performance, of the measurement of the means for obtaining the internal pressure, and this explains the difficulties encountered heretofore and now overcome.

Fig. 5 shows part of a battery according to the invention comprising a casing 217 wherein

there are assembled under pressure, as hereinabove set forth, a set of positive electrodes 210 alternating with negative electrodes 218. The negative electrodes consist essentially, in the discharged condition of the battery (as disclosed in my above-identified co-pending application) of zinc oxide, the positive electrodes being composed essentially of silver. An alkaline electrolyte (not shown) permeates the sheet material 220, here indicated to consist of cellophane, which separates adjacent electrodes from one another.

In the light of the foregoing it will, of course, be apparent that the battery shown in Fig. 5 is merely an illustrative example and that departures therefrom are permissible within the spirit and scope of the appended claims.

I claim:

1. An electric accumulator, which comprises at least one positive electrode containing silver, at least one negative electrode containing zinc juxtaposed with said positive electrode, a semi-permeable material between said electrodes, an alkaline electrolyte impregnating said electrodes and said material and exerting a swelling influence on said material, the swelling of said material applying the same against said electrodes under a pressure at least 15 kg./sq. dm.

2. In an electric accumulator, in combination, a casing; a plurality of elements juxtaposed in said casing including at least one positive electrode, at least one negative electrode, a semi-permeable material, and means including said material separating electrodes of opposite polarity; and an electrolyte in said casing permeating said electrodes and said material, said electrolyte having a swelling influence upon said material,

5 the ratio of free space, computed as the difference between the dimension of said casing normal to said electrodes and the combined thickness of all of said elements other than said material, to the total thickness of said material, when in the dry state, being within a range of substantially from 2 to 3.

10 3. In an electric accumulator, in combination, a casing; a plurality of elements juxtaposed in said casing including at least one positive electrode containing silver, at least one negative electrode containing zinc, and a semi-permeable material between adjacent electrodes of opposite polarity; and an alkaline electrolyte in said casing permeating said electrodes and said material, said electrolyte having a swelling influence upon said material, the ratio of free space, computed as the difference between the dimension of said casing normal to said electrodes and the combined thickness of all of said elements other than said material, to the total thickness of said material, when in the dry state, being within a range of substantially from 2 to 3.
